UNITED STATES PATENT OFFICE

JOHN F. CURTIS, OF CHICAGO, ILLINOIS, ASSIGNOR TO O. F. JORDAN COMPANY, OF EAST CHICAGO, INDIANA, A CORPORATION OF INDIANA

SPRAY NOZZLE

Application filed January 27, 1926. Serial No. 84,039.

This invention relates to improvements in spray nozzles and it consists of the matters hereinafter described and more particularly pointed out in the appended claims.

5 The primary object of the invention is to provide a simple and efficient spray nozzle especially adapted for use in rail joint oilers to form a substantially conical spray of a peculiar kind wherein the spray is heavier at 10 diametrically opposite points in one plane than it is at diametrically opposite points in another plane.

A further object of the invention is to provide a spray nozzle wherein the desired 15 intensity of the spray may be readily attained by a simple manipulation of the parts thereof from outside the nozzle casing.

Still another object of the invention is to provide a spray nozzle including a tapered 20 valve head adapted to coact with a similarly tapered valve seat like discharge aperture formed in the transversely curved wall of the nozzle casing, whereby said aperture is of a peculiar formation in that at diametrically 25 opposite points in one plane it presents in connection with the valve head a greater surface and consequent friction to the spraying fluid, than is presented to the fluid at diametrically opposite points in a plane at a 30 right angle to the first so that a substantially conical shaped spray of a cross section corresponding to a roman capital "O" is produced. These objects of the invention as well as others, together with the many advantages 35 thereof will more fully appear as I proceed with my specification.

In the drawings:—

Fig. 1 is a view in elevation of a pair of 40 associated spray nozzles embodying my invention in the relative position they occupy with reference to a rail and the joints thereof when embodied in a rail joint oiler.

Fig. 2 is a longitudinal sectional view on an enlarged scale, through one of the nozzles 45 shown in Fig. 1.

Fig. 3 is a transverse vertical section through the same as taken on the line 3—3 of Fig. 2.

Fig. 4 is a view in front elevation of the 50 same.

Fig. 5 is a diagrammatic view illustrating the cross sectional shape of the substantially conical spray produced by my improved nozzle.

Referring now in detail to that embodiment of my invention illustrated in the accompanying drawing, 1—1 indicate tubular nozzle casings, each closed at its bottom end as at 2 and each made integral with conduits 3—3 in which equal pressures are maintained. The conduits 3 form part of a rail joint oiler and when in their normal operative position thereon are disposed in vertical planes equally spaced on each side of the rail 4, the abutting ends of the rail sections 60 thereof being operatively connected together by joint or fish plates 5 and bolts 6 in the manner well known.

Although the nozzle casings 1—1 are made integral with the conduits or members 3 70 which are connected to a suitable source of spraying fluid under pressure, said nozzle casings are inclined outwardly from the plane of the associated member 3 and as the structure in each casing is the same a detailed 75 description of one will suffice for both.

Each nozzle casing which is tubular in cross section includes a front wall 7 and a rear wall 8 the terms "front wall" and "rear wall" being relative only as to their positions 80 with respect to the rail. Made integral with and arranged at a right angle to the rear wall is a tubular extension 9 which defines a chamber 10 communicating with the interior of the nozzle casing. In the front wall 7 of the 85 nozzle casing and coaxial with said extension is provided an inwardly tapering valve seat like discharge aperture 11, the defining surface of which is radial with respect to the axis of the nozzle casing on a transverse 90 plane. It is apparent from a comparison of Figs. 2 and 3 that due to the transverse curvature of the front wall 7 of the nozzle casing, the discharge aperture is of a greater radial length at diametrically opposite points in the 95 longitudinal plane of the casing than it is at diametrically opposite points in a plane at a right angle thereto, which of course is the transverse plane of the casing.

Within the nozzle casing and coaxial with 100

the tubular extension and discharge aperture is provided a valve member 12 including a stem 13 and a head 14 on one end thereof, which is tapered toward said stem, in accordance with the taper of said aperture. The opposite end of said stem, extends through the end wall of the tubular extension of the nozzle casing and upon the same is threaded a nut 15, a washer 16 being interposed between said end wall of the extension and said nut. It will be noted from Figs. 2 and 3 that the bearing of said stem in said end wall of the extension is relatively short and it is not a tight fit and it is therefore capable of a limited amount of wobbling movement therein so that when the fluid under pressure fills the nozzle casing, it will also fill the extension chamber and the spraying fluid therefore will exert its pressure in a direction parallel with the valve stem and will truly center the head thereof with reference to the discharge aperture. The amount of space or opening between the valve stem head and valve seat, may of course be adjusted to the desired amount by screwing the nut inwardly or outwardly upon the bolt and should it be desired to close the head upon said aperture, as when the rail joint oiler is only in transit, the nut may be screwed down to bring the head to seat upon said aperture.

By the formation of the aperture in the front wall of the nozzle casing as before described and thus providing a differential in the radial length at the different points on the casing part defining the same, a peculiar condition arises in that the spraying fluid meets with more surface friction and therefore more resistance at the top and bottom parts of the valve seat (considering the longitudinal axis of nozzle casing) than it does at the sides thereof whereby the spray which issues from the nozzle in the form of a cone, is thinner at the top and bottom than at the sides so that it is of a differential cross section form corresponding to a roman capital "O" as shown in Fig. 5.

Due to the inclination of the nozzle casing, the spray thus formed is so directed toward the rail as to apply more of the spraying fluid upon the bolts and adjacent horizontal portions of the joint plates than upon the top or bottom of the same, in this manner applying more of the fluid where it is most needed and preventing the application to the wheel tread portion of the rail. Again with such a substantially conical spray, a greater quantity thereof is directed between the web of the rail and the joint plates at the ends thereof, in the passage of the rail joint oiler as a whole over the rails.

My improved nozzle comprises but a few parts which may be readily assembled and which are of such rugged construction as to amply withstand the hard use it receives in service.

While in describing my invention, I have referred to certain details of construction as well as form and arrangement of parts thereof, the same is to be taken for the purpose of illustration only so that I do not wish to be limited thereto except as may be pointed out in the appended claims. 70

I claim as my invention:

1. A spray nozzle for spraying oil and the like upon rail joints embodying therein a depending tubular casing having an inwardly tapering discharge opening in one side thereof, a valve stem arranged transversely of and within the casing coaxially with said opening and a tapered head at the free end of the valve stem disposed in said opening which opening and head are so relatively formed as to produce a substantially cone shaped spray having an uninterrupted differential cross section corresponding to a roman capital O and therefore heavier at diametrically opposite points in one plane than at diametrically opposite points in another plane, the tubular casing being so disposed relative to the rail joint to be sprayed that the heavier portions of the spray are disposed at the sides and the thinner portions are disposed at the top and bottom of the rail joint. 80 85 90

2. A spray nozzle for spraying oil and the like upon rail joints embodying therein a hollow casing having an inwardly tapering discharge opening therein, a tapered head member in said discharge opening, which opening and head are so relatively formed as to produce a substantially cone shaped spray having an uninterrupted differential cross section corresponding to a roman capital O and therefore heavier at diametrically opposite points in one plane than at diametrically opposite points in another plane, the hollow casing being so disposed relative to the rail joint to be sprayed that the heavier portions of the spray are disposed at the sides and the thinner portions are disposed at the top and bottom of the rail joint and said head being loosely supported so that it is centered in the opening by the oil discharging therefrom under pressure. 100 105 110

3. A spray nozzle for spraying oil and the like upon rail joints embodying therein a hollow casing having an inwardly tapering discharge opening therein, a valve stem arranged in said casing substantially coaxially with said opening and a tapered head at the free end of the valve stem disposed in said opening which opening and head are so relatively formed as to produce a substantially cone shaped spray having an uninterrupted differential cross section corresponding to a roman capital O and therefore heavier at diametrically opposite points in one plane than at diametrically opposite points in another plane, the hollow casing being so disposed relative to the rail joint to be sprayed 115 120 125 130

that the heavier portions of the spray are disposed at the sides and the thinner portions are disposed at the top and bottom of the rail joint, and said valve stem being loosely held to thereby loosely support said head so that the head is centered in the opening by the oil discharging therefrom under pressure.

In testimony whereof, I have hereunto set
10 my hand, this 19th day of January, 1926.
JOHN F. CURTIS.
